(57) **CLAIM**

The ornamental design for an electrode foil for capacitor, as shown and described.

DESCRIPTION

FIG. 1 is a front elevational view of an electrode foil for capacitor showing our new design;

FIG. 2 is a top plan view thereof;

FIG. 3 is a right side elevational view thereof;

FIG. 4 is a left side elevational view thereof;

FIG. 5 is a rear elevational view thereof; and,

FIG. 6 is a bottom plan view thereof.

The broken line in the drawings is included for the purpose of illustrating environment and forms no part of the claimed design.

The dash-dot line represents the boundary of the claimed design.
